HERMAN C. BREHMER, OF PHILADELPHIA, PENNSYLVANIA, ASSIGNOR TO H. W. BUTTERWORTH & SONS COMPANY, OF PHILADELPHIA, PENNSYLVANIA, A CORPORATION OF PENNSYLVANIA.

PRESSURE-MOTOR.

1,144,322.

Specification of Letters Patent. Patented June 22, 1915.

Original application filed June 12, 1914, Serial No. 844,635. Divided and this application filed February 3, 1915. Serial No. 5,836.

To all whom it may concern:

Be it known that I, HERMAN C. BREHMER, a citizen of the United States, and resident of Philadelphia, county of Philadelphia, 5 and State of Pennsylvania, have invented an Improvement in Pressure-Motors, of which the following is a specification.

This application is a division of application Serial No. 844,635, filed June 12, 1914 10 for guide mechanism for cloth, and the present invention relates to a pressure motor and consist of certain improvements which are fully set forth in the following specification and shown in the accompanying drawings 15 which form a part thereof.

The object of my invention is to provide a motor device controlled by a suitable fluid pressure adapted more particularly for operation by a trip mechanism whereby all 20 parts of said motor are constructed for sensitive and delicate action, being adjusted to respond substantially instantaneously upon a variation of the normal working conditions.

25 It has for a further object to provide a motor wherein a movable part thereof is accurately and positively guided while the bearing of said movable member is so constructed that other adjustments of other adjuncts of the motor have no effect upon the said movable part.

With the above and other objects in view, the nature of which will be more fully understood from the description hereinafter, 35 the invention consists in the novel construction of motor device as hereinafter more fully described and defined in the claims.

Referring to the drawings: Figure 1 represents a section on line $x-x$ of Fig. 2; 40 Fig. 2 represents a sectional elevation of a motor device embodying my invention; Fig. 3 represents a plan of one of the bearing members forming a part of the motor construction.

45 16 designates a post of suitable form and mounted upon a suitable fixed support in order to form a hanger or retaining means for the tubular extension 20 of a cylinder 21, the said extension projecting through the 50 post 16 and being screw threaded to receive the nut 22 by which the parts are secured in assembled condition. One end of the cylinder 21 is closed and provided with exhaust

ports 23, while the opposite open end has screw threaded engagement with a casing 55 24, within which is located the valve mechanism for controlling the operation of the parts contained within the cylinder 21. These parts comprise a piston 25 mounted for free reciprocatory movement within the 60 cylinder and carrying a plunger 26 at one side which passes through and projects from the extension 20 for the purpose of actuating a suitable mechanism which is adapted to be automatically controlled by movements 65 of the said plunger. The upper portion of this casing 24 acts as a head or closure for the cylinder 21. The opposite side of the piston 25 is provided with a stem 27 journaled in an apertured disk or spider 28 by 70 which the said piston is accurately centered so that it may reciprocate properly without binding or becoming distorted in use.

29 designates a spring encircling the plunger 26 and held between the piston 25 and 75 the extension 20 so that its tendency is to return the piston 25 to normal position after the motive fluid has actuated the said piston.

In connection with the member 28 it will be noted that the outer ends of the radial 80 arms thereof are circumferentially milled or machined as shown at 30, whereby one portion of the bearing member accurately fits the interior of the cylinder 21, while the remaining portion 30 seats between the shoulder 31 of the cylinder 21 and the threaded part 32 of the casing 24. It will further be seen that the part 30 has a thickness preferably less than the space in which it is seated in order to provide a slight clearance when 85 the casing 24 has been properly assembled on the cylinder 31. This clearance prevents the spider 28 from being clamped in a fixed manner between the two parts and thus effectively eliminates twisting or buckling 90 which would impair the proper movement of the piston 25.

33 designates the body portion of a valve member having oppositely disposed stems 34 and 35, the former passing through the 100 closure cap 36 at one side of the casing, while the latter projects through the opposite side and is held by a screw 37 and washer 38 or like fastening means, though it will be noted that this connection is not such as to prevent 105 free movement of the body portion within

the casing 24. The body part 33 is suitably bored to form intersecting channels 39 and 40, the former having communication with a port 41, which in certain positions of the 5 valve body comes into alinement with the inlet conduit 42 for compressed air or other motive fluid.

43 designates the valve plug having a portion of its length of tubular form and seating within the bore 40. This plug, as here 10 shown, is provided with a pair of ports 44 adapted to aline at certain times with similar ports 45 provided in the wall of the casing 24 and communicating with the interior 15 of the cylinder 21. When the two sets of ports 44 and 45 are in alinement, the motive fluid has free passage into the cylinder 21 and to one side of the piston 25, as will be understood.

20 46 designates an exhaust port or channel cut in the outer face of the valve piece adjacent the ports 44 and preferably extending from one side of the plug to the other so that when it in turn is in alinement with 25 the ports 45 the pressure in the end of the cylinder 21 will be relieved and the motive fluid exhausted by way of the port 46 into the interior of the casing and from which it has free access to the outside of the casing 30 by way of the opening 47 or the like. This opening 47 permits access to the valve body, and it will be noted that one end of the port 40 is closed by a screw 48 so that upon its removal a suitable implement or tool may be 35 inserted to adjust the valve piece 43 for wear. The valve piece is ordinarily fixed in adjusted position by a set screw 49 in alinement with which is an opening 50 in the casing so that the screw may be readily manipulated. The screw 51 which is threaded 40 through the casing 44 serves as a stop to limit the throw of the valve body.

52 designates a rod adjustably mounted on the projecting end of the valve stem 34 45 and having one end threaded to receive a counterweight 53 while intermediate its length there is a trip arm 54 which extends into the path of movement of the trip finger 55. The counterweight 53 is normally adjusted so that the valve body 33 is positioned 50 with the ports 44 in register with the ports 45, and since at this time the inlet port 41 is in alinement with the channel 42 the motive fluid has a free passage into the cylinder 55 21 and therefore maintains the plunger 26 outwardly pressed.

It will be understood that the trip finger 55 may form a part of any type of machine in which regulation is required to be automatically obtained through the operation of the plunger 26 and the trip finger is, of course, so adjusted and arranged as to cause operation of the motor at the proper time. Under normal conditions the counterweight 60 53 holds the valve stem 34 in a position to

admit pressure fluid to one side of the piston 25, thus forcing the plunger 26 outwardly in order to bear against and operate the parts controlled thereby. The action of the trip finger is to shift the arm 54 in such a manner as to raise the rod 52 against the weight 53 and thereby swing the valve piece 43 into exhaust position with the channel 46 in register with the ports 45. In consequence 70 the pressure within the cylinder 21 is relieved and the spring 29 forces the plunger inwardly to its inoperative position. Attention is particularly directed to the function of the spider bearing member 28 which serves to accurately maintain the plunger 75 properly centered, as well as the piston itself, and adjustment of the parts or a change of relation between them does not interfere with the proper alinement of the spider member.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification 90 in various particulars without departing from the spirit or scope of the invention.

Having now described my invention, what I claim as new and desire to protect by Letters Patent is:—

1. In a device of the character stated, a suitable supporting frame, a cylinder mounted on said frame, a head detachable from the cylinder, a piston in said cylinder having a plunger at one end projecting through and guided by the cylinder wall, a stem at the opposite end of said piston wholly within the cylinder, a bearing member snugly fitting the bore of said cylinder to hold it against lateral movement but movable axially of said cylinder to a slight extent for guiding said stem and maintaining said plunger centered in the cylinder, and means to operate said piston and plunger.

2. In a device of the character stated, a suitable supporting frame, a cylinder mounted on said frame, a piston positioned in said cylinder having a plunger at one end projecting through and guided by the cylinder wall and also having a stem at its opposite end, a spider member having a central opening to guide and form a bearing for said stem, said spider member having its peripheral portion circumferentially notched to accurately fit the bore of said cylinder and provide extended portions loosely fitting over the end of the wall of the cylinder, and means to operate said piston and plunger, said means having a port-

tion secured to the lower end of the cylinder and holding the spider member in loose operative relation with the cylinder.

3. In a device of the character stated, a suitable supporting frame, a cylinder fixed to the frame and having one end closed, a piston in said cylinder having a plunger at one end guided through the closed end of the cylinder and also having a stem at the other end, a valve mechanism secured to the open end of the cylinder and forming an annular space between it and the end of the cylinder, a guide for the stem of the piston provided with openings through it and also having its periphery arranged to fit the cylinder whereby it is centered, and having also radial portions loosely fitting the annular space and permitting slight movement in the axial direction of the piston whereby the guide is accurately positioned and at no time clamped against movement.

4. In a device of the character stated, a cylinder open at one end, a valve casing secured to the open end of the cylinder to close it and providing an annular clearance between the valve casing and the interior of the cylinder wall said valve casing having a centrally arranged port opening into the cylinder, a piston arranged within the cylinder and having a plunger projecting through one end of the cylinder and also having a stem at the other end extended down to a position in alignment with the port, and a bearing member fitting the bore of the cylinder and through which the stem extends to maintain the stem centered in the cylinder and said bearing member having radial portions extending into the annular clearance between the casing and cylinder and with capacity for slight movement axially of said cylinder.

5. The combination of a cylinder, a valve casing secured in one end of the cylinder

and providing lateral clearances of the wall of the cylinder arranged annularly about its axial center, valve devices for controlling a pressure fluid to and from the cylinder, a piston within the cylinder having a plunger portion extending from one side and with a stem portion extending from the other side in axial line with the center of the cylinder, and a bearing member in which the stem is guided said bearing member closely fitting the interior of the cylinder whereby it is centralized and having lateral extensions projecting into the lateral clearances between the cylinder and valve casing.

6. The combination of a cylinder, a valve casing secured in one end of the cylinder and providing lateral clearances of the wall of the cylinder arranged annularly about its axial center, valve devices for controlling a pressure fluid to and from the cylinder, a piston within the cylinder having a plunger portion extending from one side and with a stem portion extending from the other side in axial line with the center of the cylinder, and a bearing member in which the stem is guided said bearing member closely fitting the interior of the cylinder whereby it is centralized and having lateral extensions loosely projecting into the lateral clearances between the cylinder and valve casing with capacity for small axial movement relatively to the cylinder and valve casing and said bearing member having a hub with radially extending portions providing passages between them.

In testimony of which invention, I here-
unto set my hand.

HERMAN C. BREHMER.
